SHEET-WINDING MECHANISM FOR PLAYER-PIANOS.

1,331,870.

Specification of Letters Patent.

Patented Feb. 24, 1920.

Application filed February 5, 1916. Serial No. 76,387.

To all whom it may concern:

Be it known that we, ERNST D. MOORE, a citizen of the United States, and STANLEY L. FISHER, a subject of the King of Great Britain, both residing in Saybrook, county of Middlesex, and State of Connecticut, have invented certain new and useful Improvements in Sheet-Winding Mechanism for Player-Pianos, of which the following is a full, clear, and exact description.

This invention relates to note sheet centering mechanism for player pianos, and one of the objects of the invention is the provision of means for causing the sheet to be wound up tightly and in a proper manner on the take-up spool so that when the sheet is re-rolled on the music roll it will be so positioned on the latter as to induce proper rendition the next time the roll is played. More especially, our object is to provide means for exerting pressure on the edges of the note sheet as it is wound on the take-up spool in such a manner as to prevent the deviation of the sheet from its proper path, together with means for regulating the pressure on the edges of the note sheet and relieving the pressure when a certain maximum is attained. Devices for exerting pressure on the edges of the sheet as it winds on the take-up spool have been heretofore devised, but where the pressure devices are not carefully controlled the edges of the sheet quickly become torn and mutilated. In accordance with our invention, however, the sheet is wound up truly on the take-up spool without mutilation or damage.

To these and other ends, the invention consists in the novel features and combinations of parts to be hereinafter described and claimed.

In the accompanying drawings,

Figure 1 is a front elevation of note sheet centering mechanism embodying our invention, with certain parts broken away, the music roll being in the playing position;

Fig. 2 is a rear elevation of the mechanism, showing the music roll holding device in the position which it assumes when the music roll is removed;

Fig. 3 is a plan view of the supporting means for the music roll, the top of the spool box being omitted;

Figs. 4 and 5 are detail views of the music roll-supporting spindles; and

Figs. 6 and 7 are details of the connection between the pneumatic and the actuating levers for the pressure devices associated with the take-up spool.

The spool box 10 is of the usual type and supports the customary tracker bar 11 in the ordinary manner. This tracker bar may be fixed in position by screws 12, as shown in the drawings, or, in some cases, may be mounted to allow adjustment laterally of the box by means well known in the art. The music roll 13 carrying the note sheet 14 is mounted above the tracker bar in the customary location by means of spindles 15, 16, and the take-up spool 17 is located in the customary manner beneath the tracker bar and supported by spindles 18, 19, all of said spindles having bearings in the side walls of the box, as shown.

Referring now to the mechanism for supporting and centering the music roll 13, it will be observed that the spindle 15 is in the nature of an enlarged hub on a stem 15^a, said spindle or hub being located at the inner face of the box wall, and guided for lengthwise movement in a bushing 20 in said wall, as shown in Fig. 4. At its inner end, the spindle 15 is provided with a laterally projecting flange or collar 21 having a vertical face disposed toward the adjacent music roll head 13^a. Projecting inwardly from the collar 21 is a centering projection or boss 22 with an inclined periphery adapted to enter a correspondingly shaped but larger recess 23 in the roll head 13^a. The arrangement is such that while the vertical inner surface on the collar 21 makes contact with the end face of the roll head 13^a, the boss 22 is of such size and shape as not to bottom in the recess or socket 23. The spindle 16 is generally similar to the spindle 15, being mounted on a stem 16^a and guided for end-wise movement in a bushing 24 of the box wall. Near the inner end of the spindle is a collar 25 similar to the collar 21 and having a vertical face to contact with the end surface of the roll head 13^b. Projecting from the inner end of the spindle 16 is the usual driving lip 26 adapted to project into a socket 27 in the roll head 13^b,

but the arrangement is such that while the inner face of the collar 25 engages the end face of the roll head 13^b, the lip 26 and the adjacent spindle end do not bottom in the socket 27. Thus, it will be understood that when the music roll is inserted between the spindles 15, 16, said spindles will contact only with the end surfaces of the corresponding heads of the music roll. The collars 21, 25 prevent the spindles from engaging the bottoms of the respective sockets, which is a feature of advantage that is more particularly explained hereinafter. A knurled collar 28 on the spindle 16 facilitates the turning of said spindle by hand so as to engage the lip 26 non-rotatively with a rectangular portion of the socket 27 in the usual manner so that the roll may be driven by the rotation of the spindle 16.

20 The music roll is driven from the stem or shaft 16^a by means of suitable connections with an appropriate motor (not shown), which motor is also operatively connected with the shaft or spindle 19 of the take-up roll so as to drive the latter in the usual manner.

The collars 21, 25 of the respective roll-supporting spindles are yieldingly held in contact with the respective roll heads by 30 mechanism which may be constructed substantially as follows: On the stem or shaft 15^a at a point outside of the spool box are mounted two spaced collars 29, 30, which may be secured on the shaft by means of 35 screws, as shown. Collars 31, 32 are mounted on the shaft 16^a in a similar manner. The collars 29, 31 nearest the spool box are adapted to abut against the respective side walls of the box so as to limit the inward 40 movement of the respective spindles, and these collars are so adjusted that when they contact with the respective walls of the box or other suitable abutments, the collars or shoulders 21, 25 are equidistant from the 45 center of the spool box, and are slightly nearer to each other than are the outer surfaces of the music roll heads. In other words, said collars are spaced apart at a distance which is less than the maximum 50 length of the music roll. Between the collars 29, 30, a bar 33 engages the shaft 15^a by means of an inturned end portion 34 which is adapted to abut the collar 29 in order to move the shaft toward the music roll and to 55 abut the collar 30 in order to move the shaft away from the music roll. A similar bar 35 has an inturned end portion 36 embracing the shaft 16^a between the collars 31, 32. The bars 33, 35 are pivoted at 37, 38 60 respectively to a lever 39 which is swiveled to the back of the box at 40. The swivel mounting 40 of lever 39 is centrally located between the pivots 37, 38 so as to equalize the movement of the two spindles 15, 16 and 65 insure their having a symmetrical relation

to a predetermined center line at all times, irrespective of the lengthwise adjustment of the spindles.

In the form shown, the spindles are normally held in their innermost position by 70 means of a spring 41 attached to the music box at 42 and to the lever 39 at 43. When the spindles 15, 16 are moved away from the music roll to free the latter, and then released, the spring 41 returns the parts to the 75 normal position in an obvious manner so that the spindles are at the limit of their inward movement with the collars 29, 31 in abutment with the sides of the box. When a new music roll is to be inserted, the spindles 80 are moved away from each other, for example, by grasping the knurled collar 28 on spindle 16, and when the collars 21, 25 of the respective spindles are engaged with the end faces of the roll heads in the manner 85 previously described, it will be found that the note sheet is symmetrically located with respect to a given center line, such as the center line of the music box, because in all music rolls with which we are familiar the 90 two heads are symmetrically formed to the extent that the end surfaces for engaging the collars 21, 25 are equidistant from the center of the note sheet. It will be understood, therefore, that the roll centering 95 device just described can be used to center music rolls of many different types without regard to the depth of the sockets in the roll heads so long as such sockets have the usual minimum depth. This is effected by making 100 the socket-engaging projections on the spindles so shallow that they will not engage the bottoms of the sockets of any of the standard music rolls.

If, after assembling, it is found that the 105 spindles do not have the proper symmetrical relation to a predetermined center, the necessary correction can be effected by shifting the shaft collars in an obvious manner. The collars on each shaft should obviously be 110 spaced apart at a sufficient distance to permit the necessary swinging movement of the bars 33, 35. Ordinarily, the center with respect to which the collars 21, 25 are symmetrical is in a vertical plane passing 115 through the center of the tracker bar scale, *i.e.*, the series of perforations in the tracker bar corresponding to the number of notes of the piano which are to be played, but naturally if the tracker bar is to be adjusted 120 out of its normal position, say for the purpose of transposing the key, the music roll will be longitudinally displaced with respect to the tracker bar.

Referring now to the take-up spool 17, it 125 will be observed that the same is provided with movable end flanges 44 adapted to make contact with the edges of the note sheet 14. In the particular form illustrated, these flanges 44 are normally pressed away from 130

the ends of the spool proper by coil springs 45 (of which only one is shown) located in suitable sockets in the end of the spool and embracing the respective spindle or shaft 5 portions 18, 19. The take-up spool is prevented from endwise movement by collars 46 screwed on the spindles 18, 19 at the inner portion of the box, said collars abutting against bushings 47 which form bearings for 10 the spindles. These collars 46 are adjustable in an obvious manner so that the take-up spool may be adjusted laterally in the box. Each flange 44 has a hub portion 48 contacted by the forked portion 49 of an elbow lever 50, pivoted to swing in a vertical plane. In the form shown, each lever 50 is pivoted or fulcrumed at 51 on a suitable support in the lower part of the box. The levers 50 are connected with a suitable actuating device, such as a pneumatic 52. In the particular form shown, the lower inwardly extending arms 53 of levers 50 are interconnected by a pin 54 which passes through a forked extremity 55 on one of the levers, 25 which forked extremity straddles the extremity of the other lever and is slotted in order to receive said connecting pin. The connection between the levers 50 and the pneumatic 52 is preferably made by means 30 of a link 56, preferably of wire, connected at its upper end with the pin 54, and at its lower end with a pallet or valve 57 associated with the lid of the pneumatic. This valve is acted on by a leaf spring 59 carried by the lid or leaf of the pneumatic, and said spring normally holds the valve in position to close a relief opening or air inlet 58 in the lid of the pneumatic. The spring bears on a washer 57^a surrounding the link 40 56 above the valve 57. The valve or pallet is supported from beneath by a washer or projection 57^b on the link, which guides the valve relatively to the air inlet without substantially obstructing said inlet. A screw 45 60 passing through the spring 59 permits the action of the latter to be adjusted so that the force by which the valve 57 is held seated may be varied for the purpose hereinafter described.

50 It will be evident from the foregoing description that as the pneumatic 52 is collapsed, the levers 50 will be swung on their pivots 51 in such a way as to move the flanges 44 of the take-up spool inwardly toward the edges of the note sheet in opposition to the springs 45. The pneumatic is exhausted through a tube 61 connected with suitable pressure reducing apparatus (not shown), the connection of tube 61 with the 55 pneumatic being made by way of a small bleed opening 62, whereby the collapse of the pneumatic is retarded. When the air is admitted to the pneumatic by the opening of the relief valve 57 or otherwise, the 60 pneumatic is restored to the normal expand- ed condition by means of a spring 36 or similar device. The pneumatic is also normally held in the expanded condition by means of the springs 45 acting on the flanges 44 and the levers 50, as will be obvious. 70 The tension of the spring 59 is greater than the force required to overcome the springs 45, and therefore when the device is not in use the flanges 44 are unyieldingly connected with the movable member of the pneumatic. 75

The operation of the mechanism will be more or less obvious from the foregoing description. The music spool 13 is first mounted between the spindles 15, 16 in the manner previously described so that the openings of the note sheet will coincide with the corresponding openings of the tracker bar. The pressure reducing apparatus now being put into operation, the winding up of the note sheet on the take-up spool is commenced 80 by the usual mechanism and as the tube or conduit 61 of pneumatic 52 is connected with the pressure reducing apparatus, the pneumatic will collapse and the flanges 44 of the take-up spool will be forced inward 85 against the edges of the note sheet. As the flanges 44 and levers 50 are symmetrically formed and located, the note sheet will be accurately centered on the take-up spool and caused to wind up tightly and truly. 90 The flanges or movable spool members 44 do not contact with the edges of the note sheet until several layers have been wound on the take-up spool. This is due to the provision of the bleed 62, which delays the collapse of the pneumatic to the necessary extent. Thus, when the flanges 44 come in contact with the edges of the sheet, their action is resisted by several layers of the note sheet, as well as by the springs 45. Thus, 100 105 the pressure exerted on the edges of the sheet at this time is sufficient to center the sheet properly but not to tear or damage the same. The pressure exerted on the edges of the sheet by the flanges cannot increase 110 to such an extent as to tear or injure the sheet because if the pneumatic 52 is exhausted to a certain predetermined degree, the pressure of spring 59 is overcome and 115 the lid of the pneumatic parts slightly from the pallet 57 so that further inward pressure of the flanges on the sheet is prevented. The spring 59 can be so set by means of its regulating screw as to determine the exhaustion of pneumatic 52 which is sufficient to open 120 the relief inlet by means of pallet 57, and therefore it is possible to so adjust the apparatus that the end flanges or members 44 of the take-up spool will not exert pressure 125 on the note sheet in excess of a predetermined maximum pressure, which is variable at will. When the pallet opens to admit air into the pneumatic through the relief inlet, the parting of the pallet from its seat is only slight and momentary for the en- 130

trance of air into the pneumatic causes the movable member thereof to immediately contact again with the pallet and seat the latter. The described connection between the pneumatic and the movable flanges or pressure devices acts in the nature of a lost motion connection when a certain pressure is attained.

The flanges 44 remain in contact with the edges of the note sheet until the unrolling operation is completed. The effect of this contact and constant pressure is most beneficial as it prevents side slipping and consequent loose winding of the note sheet on the take-up roll, and is of great aid in maintaining by its guiding force correct registration between the perforations in the note sheet and those of the tracker bar. As the note sheet is thus wound up on the take-up spool in a compact and orderly manner, it is naturally rereeled on the music roll in such a condition as to induce proper operation the next time the music roll is played.

After rendition, the pneumatic 52 opens through the action of the springs 45 and the spring 36 as air seeps into the instrument, so that the flanges of the take-up spool are moved back to their normal position. The opening of the pneumatic 52 may also be hastened by a relief valve 63, 64 connected with a tube 65 and controlled by the music roll 18. In the particular form shown, the valve 63, 64 is located on the back of the music box in proximity to the lever 39 and when the music roll is taken out after rendition, the lever 39 will be automatically swung against the pivoted member 63 to open the relief valve and thereby admit air to the pneumatic 52 through tube 65 for the purpose of restoring the flanges 44 to their initial or inoperative position. The valve 63, 64 is normally held closed by a spring 63 acting on the swinging member 63.

We do not claim herein the means for centering the music roll longitudinally relatively to the tracker bar by the spindles having means engaging the outer faces of the roll heads at the extremes of the over-all length of the roll, as claimed in our application Serial No. 106673.

We do not limit ourselves in all aspects of the invention to a device in which a slow moving or delayed action pneumatic is connected with a take-up spool flange to move the same toward the edge of the note sheet. In so far as we are aware, we are the first to provide a note sheet winding mechanism in which a controlling pneumatic for a take-up spool flange has a slow or delayed action in order that the holding effect of the flange on the note sheet may not take place prematurely, *i. e.*, before a sufficient length of the note sheet has been wound up on the take-up spool. Various changes may be made in the details of the construction without depart-

ing from the scope of our invention as set forth in the claims.

What we claim is:

1. In a device such as described, the combination of a take-up spool, devices for centering the note sheet on the take-up spool, means for exerting pressure on said devices, and regulable means for determining the maximum pressure of said devices on the sheet; substantially as described. 70

2. In a device such as described, the combination of a take-up spool, a movable end flange therefor, means for exerting pressure on said flange in the direction of the note sheet, and means for relieving the pressure 80 on the flange so that the pressure on the note sheet does not exceed a predetermined maximum; substantially as described. 75

3. In a device such as described, the combination of a take-up spool, movable devices 85 associated with the ends of said spool for centering the sheet on the spool by exerting pressure on the lateral edges of the sheet, means for pressing said devices against the sheet, and means for maintaining the pressure of such devices on the sheet at or below a predetermined maximum; substantially as described. 90

4. In a device such as described, the combination of a take-up spool, movable flanges 95 at the ends of said spool, and means for pressing said flanges against the edges of the sheet after a few layers have been wrapped on the spool, and for then maintaining the flanges in contact with the edges of the sheet 100 throughout the time that the sheet is being wound on the spool; substantially as described.

5. In a device such as described, the combination of a take-up spool, a member associated therewith for exerting pressure on one of the lateral edges of the sheet, and means for moving said member into contact with the edge of the sheet and maintaining it continuously in such contact throughout the 110 greater portion of the winding operation; substantially as described. 105

6. In a device such as described, the combination of a take-up spool, a member associated therewith for exerting pressure on one 115 of the lateral edges of the sheet, means for moving said member into contact with the edge of the sheet and maintaining it continuously in such contact throughout the greater portion of the winding operation, and means 120 for preventing the pressure on the edge of the sheet from exceeding a predetermined maximum; substantially as described.

7. In a device such as described, the combination of a take-up spool, a member associated therewith for exerting pressure on one of the lateral edges of the sheet, means for moving said member into contact with the edge of the sheet and maintaining it continuously in such contact throughout the 130

greater portion of the winding operation, means for preventing the pressure on the edge of the sheet from exceeding a predetermined maximum, said last-named means being adjustable to vary the maximum pressure; substantially as described.

8. In a device such as described, the combination of a take-up spool, movable end flanges associated therewith, means for forcing said flanges against the edges of the note sheet only after several layers have been wound on the take-up spool and for then maintaining said flanges in contact with the edges of the sheet continuously while the sheet is being wound on said spool, and means for moving said flanges away from the edges of the sheet when the winding operation is completed; substantially as described.
10. In a device such as described, the combination of a take-up spool, movable end flanges associated therewith, a pneumatic operating device, and means actuated by said operating device for gradually moving said flanges into contact with the lateral edges of the sheet and for then maintaining them in such contact continuously throughout the remainder of the winding operation; substantially as described.
15. 10. In a device such as described, the combination of a take-up spool, movable pressure devices associated with the ends of said spool, a pneumatic, and a lost motion connection between said pneumatic and said pressure devices for relieving the pressure of the latter on the sheet; substantially as described.

11. In a device such as described, the combination of a take-up spool, movable pressure devices associated with the ends of said spool, a pneumatic, and a variable lost motion connection between said pneumatic and said pressure devices for preventing the pressure of said devices on the sheet from exceeding a certain maximum; substantially as described.

12. In a device such as described, the combination of a take-up spool, a movable pressure device associated therewith for exerting pressure on the note sheet, a pneumatic for operating said pressure device, means for collapsing the pneumatic, and means for retarding collapse of the pneumatic; substantially as described.

15. 13. The combination of a take-up spool, a movable device associated therewith for exerting pressure on one of the lateral edges of the note sheet, a pneumatic, and an operative connection between said pneumatic and said movable device, including a relief valve for the pneumatic; substantially as described.

14. The combination with a take-up spool, a movable device associated therewith for exerting pressure on one of the lateral edges of the note sheet, a pneumatic for actuating

said device, a relief valve for said pneumatic mounted on the movable member thereof, and an operative connection between said valve and said movable pressure device; substantially as described.

70

15. The combination of a take-up spool, a movable member associated therewith for contacting with one of the lateral edges of the sheet, a pneumatic for actuating said member, means for retarding the collapse of the pneumatic, a relief valve for said pneumatic arranged to vary the actuation of said movable member, and means for adjusting said relief valve; substantially as described.

16. In note sheet centering mechanism, the combination of music roll-supporting spindles, a take-up spool, a device associated with said take-up spool for exerting lateral pressure on the note sheet, said last-named device having an actuating pneumatic, and means for admitting air to said pneumatic automatically when the music roll is disengaged from said supporting spindles; substantially as described.

80

17. In note sheet centering mechanism, the combination of music roll spindles, means connecting said spindles for simultaneous movement, a take-up spool, a device associated with said take-up spool for exerting lateral pressure on the note sheet, having an actuating pneumatic, and an operative connection between said spindle-connecting means and said pneumatic for admitting air to the pneumatic automatically when the music roll is disengaged from said spindles; substantially as described.

90

18. In note sheet centering mechanism, the combination of music roll spindles, a take-up spool, means associated with said take-up spool for exerting lateral pressure on the note sheet while the latter is being wound on the take-up spool, and means controlled by the removal of the music roll for moving said last-named means to an inoperative position; substantially as described.

105

19. The combination of music roll spindles, a take-up spool, means associated with said spool for exerting lateral pressure on the note sheet automatically as the sheet is wound on the take-up spool, and automatically operable means controlled by the removal of the music roll from said spindles for moving said pressure means to an inoperative position.

110

20. The combination of music roll spindles, a take-up spool, a pair of flanges on the take-up spool for engaging the edges of the note sheet, means for pressing said flanges against the edges of the note sheet as such sheet is wound on the take-up spool, and automatically operable means controlled by the disengagement of the music roll from its spindles for causing said flanges to move to the sheet-disengaging position.

120

21. The combination of a music roll, spin-

125

130

5 dles supporting the same, a take-up spool, a flange associated with said take-up spool for engaging one of the side edges of the note sheet, a pneumatic for moving said flange into engagement with the edge of the sheet as the latter is wound on the take-up spool, and means operating automatically by the removal of said music roll from said spindles for actuating said pneumatic to 10 withdraw the flange.

22. The combination of a music roll, a pair of spindles supporting the same, a take-up spool, flanges on the take-up spool for engaging the edges of the note sheet automatically during the winding of the sheet on the spool, and automatic means controlled by the removal of the music roll from its spindles for causing said flanges to move to the inoperative position.

20 23. The combination of a music roll, a pair of spindles for supporting the same, at least one of said spindles being movable longitudinally, a take-up spool, a flange on said take-up spool for engaging one edge 25 of the note sheet automatically as the sheet is wound on the spool, and automatic means controlled by the longitudinal movement of the aforesaid spindle for causing said flange to move to sheet-disengaging position.

30 24. In note sheet winding mechanism for player pianos, a take-up spool having a movably mounted flange, and a controlling pneumatic for said flange having a bleed and connections whereby the pneumatic is 35 slowly collapsed.

25. In a note sheet winding mechanism, the combination of music roll spindles, a tracker bar, a take-up spool, means associated with said take-up spool for exerting 40 lateral pressure on the note sheet as it is wound on the take-up spool, means for actuating said last means, and means controlled by the disengagement of the music roll from its supporting spindles for moving said pressure means to an inoperative position; substantially as described.

26. In a note sheet winding mechanism, the combination of music roll supporting spindles, means connecting said spindles, a 50 tracker bar, a take-up spool, movable end flanges in connection with the take-up spool, a pneumatic for actuating said end flanges, means of connection between said pneumatic and said end flanges, a relief 55 valve for the pneumatic which opens automatically when a predetermined pressure is exerted by said flanges on the lateral edges of the sheet, and a second relief valve operated by said spindle-connecting means for admitting air to the pneumatic when the 60 music roll is disengaged from its spindles; substantially as described.

27. A spool having movably mounted flanges, a pneumatic having a bleed and 65 connections for automatically moving the

flanges slowly into contact with the edges of a note sheet.

28. A spool having movably mounted flanges, a pneumatic having a bleed and connections for automatically moving the 70 flanges slowly into contact with the edges of a note sheet and maintaining them in contact therewith.

29. A spool having movable flanges and automatic pneumatic flange-controlling 75 means operable to hold the flanges from contact with the edges of a sheet during the preliminary winding thereof upon the spool.

30. A spool having movable flanges, pneumatic means and connections for moving the flanges toward the edges of a note sheet, and means for retarding the movement of said flanges to prevent contact with such edges until a multiplicity of windings has 80 taken place.

31. A spool having movable flanges, pneumatic means and connections for moving the flanges toward the edges of a note sheet, means for retarding the movement of said 90 flanges to prevent contact with such edges until a multiplicity of windings has taken place, and means for controlling the pressure of the flanges against the edges of the sheet.

32. A spool having movable flanges, means operable to move them slowly into contact with the edges of a note sheet and means for holding them in contact with such edges with constant pressure.

33. A spool having movable flanges, means for pneumatically automatically moving them toward the edges of a note sheet and means for limiting the degree of pressure of the flanges when in contact 105 with such edges.

34. A spool having movable flanges, means for automatically moving them slowly toward the edges of a note sheet and for maintaining them in contact therewith, and means for limiting the pressure of the flanges against such edges.

35. A spool having movable flanges, means for automatically moving them slowly toward the edges of a note sheet and for 115 maintaining them in contact therewith, and means for limiting the pressure of the flanges against such edges for preventing lateral movement of the sheet.

36. A spool having movable flanges, means 120 for automatically moving them toward the edges of a note sheet and for maintaining them in contact therewith, and means for limiting the pressure of the flanges against such edges for preventing lateral movement 125 of the sheet.

37. A spool having movable flanges, a pneumatic, connections between the same and the flanges and means operable in conjunction with the pneumatic for limiting 130

the pressure of the flanges against the edges of a note sheet.

38. A spool having movable flanges, operating means and connections for controlling the flanges, and means operable in conjunction with the operating means for limiting the pressure of the flanges against the edges of a note sheet.

39. A spool having movable flanges, operating means and connections for slowly controlling the flanges, and means operable in conjunction with the operating means for limiting the pressure of the flanges against the edges of a note sheet.

40. A take-up spool with automatically controlled flanges, normally out of contact with the note sheet and means for automatically bringing them into contact with the sheet after a plurality of layers has been wound upon said spool.

41. In note sheet winding mechanism for player pianos, a take-up spool, a longitudinally movable flange on said take-up spool, and a controlling pneumatic for said flange adapted to be exhausted when the note sheet is wound on said spool and having a bleed whereby the collapse of the pneumatic is retarded.

42. In note sheet winding mechanism for player pianos, a take-up spool, a longitudinally movable flange thereon, a pneumatic controlling device for said flange which is exhausted as the note sheet is wound on said spool, and means whereby the exhaust of the pneumatic flange-controlling device is caused to take place slowly.

43. In note sheet winding mechanism for player pianos, a take-up spool, a longitudinally movable flange thereon, and a slow-acting controlling pneumatic for said flange.

44. In note sheet winding mechanism for player pianos, a take-up spool, a longitudinally movable flange thereon adapted to

contact with the edge of the note sheet so as to hold the latter in a definite position 45 lengthwise of the spool, and a controlling device for said flange operative to hold the flange against the edge of the note sheet only after more than one layer of the sheet has been wound on the spool.

45. In a device such as described, the combination of a take-up spool, a longitudinally movable flange associated with one end of the spool for engaging the edge of the note sheet and thereby positioning the 55 sheet lengthwise of the spool, and a holding device for holding said flange against the edge of the note sheet only after several layers of the sheet have been wrapped on the spool.

46. In a device such as described, the combination of a take-up spool, a longitudinally movable flange associated with one end of the spool for engaging the edge of the note sheet and thereby positioning the 65 sheet on the spool, and a slow-acting pneumatic device for holding said flange against the edge of the note sheet.

47. In a device such as described, a take-up spool, a longitudinally movable flange 70 thereon, a lever connected with said flange, and a controlling pneumatic for said lever, said pneumatic having a bleed and connections for producing a slow collapse thereof and a retarded holding of the flange against 75 the edge of the note sheet.

48. In a device such as described, a take-up spool, a longitudinally movable flange thereon, and a controlling device for said flange operative to produce a retarded holding 80 of the flange against the note sheet.

In witness whereof, we have hereunto set our hands this 31st day of January, 1916.

ERNST D. MOORE.
STANLEY L. FISHER.
